FLUID PRESSURE HAMMER

Edward W. Stevens, Detroit, Mich., assignor to
Chicago Pneumatic Tool Company, New York,
N. Y., a corporation of New Jersey

Application September 25, 1928
Serial No. 308,205

2 Claims. (Cl. 121—26)

This invention relates to percussive tools operated by fluid pressure and commonly referred to as pneumatic or air hammers. More particularly it relates to pneumatic tools having automatically thrown valves and to the manner of controlling the distribution of the pressure fluid.

One object of the invention is to provide a tool of the described type characterized by simplicity of construction and high operating efficiency. Another object is to eliminate constant pressure ports which tend to shift the valve prematurely. Another object is to avoid unnecessary waste of motive fluid. Other objects will be apparent from the detailed description which follows.

The objects of the invention are accomplished by constructing the valve with carefully calculated proportions in connection with ports and passages so arranged that the effective working pressures tending to move the valve in the desired direction will be opposed only by a slight difference in the holding force, thus producing a necessarily rapid shifting of the valve at the proper instant. The valve preferably has only three diameters and four effective working surfaces or areas subjected to the pressure fluid.

In order to illustrate the invention, one concrete embodiment thereof is shown in the accompanying drawing, in which:

Fig. 1 is a side elevational view largely in section; and

Fig. 2 is a fragmentary sectional view similar to Fig. 1 but with the lower part taken at a different angle to provide a section through one of the exhaust ports, the view showing the valve and piston in different positions from those shown in Fig. 1.

The embodiment of the invention, chosen for the purpose of illustration, comprises a pneumatic riveting hammer having a cylinder 3 providing a piston chamber 3a in which reciprocates a hammer piston 4 arranged to deliver its blows to a suitable working tool such as a rivet set 5 retained in the outer end of the cylinder by a rivet set clip 6. The rear end of the cylinder is closed by a handle 7 having an extension 7a in threaded engagement with the exterior of cylinder 3. Securely clamped within a counterbore 3b of cylinder 3 by the handle is a valve case comprising interfitting parts 8 and 9 supporting a sleeve valve 10 arranged to control the distribution of the motive fluid and to move automatically in timed relation with piston 4.

Valve 10 which forms a part of the piston chamber is of simple construction and of three diameters only, namely, a small forward diameter

part 10a, a slightly larger diameter part 10b at the rear, and a substantially central flange 10c. The valve accordingly has but four pressure areas, namely, the two extreme ends of the valve and the two faces of flange 10c.

In Fig. 1, valve 10 has just shifted forwardly and piston 4 is beginning its forward or working stroke. Motive fluid entering the hammer through the handle duct 7b passes into the rearward end of the valve case through an annular series of passages 11 communicating with an annular groove 11a which in Fig. 1 is uncovered by the valve 10 to admit the motive fluid directly into the rear end of the piston chamber. With piston 4 in the position shown, this motive fluid has access to the pocket rearwardly of the piston through a restricted passage or by-pass 12. The air trapped in front of the piston is vented to atmosphere through one or more passages 13 communicating by ports 13a with the chamber rearwardly of flange 10c of the valve whence the air passes to atmosphere through ports 14a (Fig. 2) communicating with a series of passages 14 extending to atmosphere. Just before piston 4 delivers its blow to the rivet set 5, it uncovers a port 15a communicating with an axial shift passage 15 which directs pressure fluid from the piston chamber through a greatly restricted port 15b directly against the forward face of the valve flange 10c. This face or valve area exceeds the area provided by the rearward edge of the valve and although the port 15b is very small the chamber with which it communicates is small also with the result that rearward movement of the valve is promptly initiated. Shortly after its initial movement, flange 10c of the valve uncovers a live air port 16a which is supplied with motive fluid through a passage 16 communicating with one of the live air passages 11. The live air admitted by port 16a augments the pressure fluid supplied through restricted port 15b and moves the valve promptly to the rearward position shown in Fig. 2, whereupon the annular groove 11a is sealed by part 10b of the valve while part 10a uncovers a series of vent ports 14b for the rear end of the piston chamber which open directly into atmospheric vent passages 14. On its rearward movement flange 10c of the valve has closed ports 13a and 14a but opened ports 13b (Fig. 1) whereby the live motive fluid admitted to the chamber forwardly of valve flange 10c by port 16a has access through passages 13 to the forward end of the piston chamber to drive the piston rearwardly. The small size of port 15b of shift passage 15 prevents any appreciable loss of motive

fluid through shift passage 15 into the piston chamber prior to the sealing of port 15a by piston 4.

As piston 4 moves rearwardly and enters sleeve 5 valve 10 it seals off vent ports 14b and compresses the air which is trapped in the cushion pocket provided by valve case part 9. This trapped and compressed air acts against the rearward edge of valve 10 and continues to have access thereto even 10 after piston 4 has passed beyond the valve by means of passage 12 (Fig. 1). In the meantime, piston 4 on its rearward movement has uncovered port 15a thereby assisting, through shift passage 15 and restricted port 15b, in reducing the pressure in the valve chamber forwardly of flange 10c to that obtaining in the forward piston chamber. As a consequence, the pressure against the rearward edge of the valve preponderates and the 15 valve moves forwardly to the position shown in Fig. 1, thus completing the cycle of operation.

The restriction of the port 15b is a novel and essential feature of the present invention and results from the discovery that a restriction in the shift passage at this point, namely, immediately 20 adjacent the valve is sufficient to initiate shifting movement of the valve by the high velocity jet of air entering a very restricted chamber and impinging directly against the valve. The shifting of the valve may be completed by live air admitted 25 through a port such as 16a uncovered by such initial movement of the valve and the restriction of the shift passage can be made sufficient to avoid any tendency of the valve to flutter by reducing the amount of air which can escape into the piston 30 chamber. It also has the effect of greatly reducing the air consumption of the hammer since the amount of live air which can escape through restricted port 15b and out into the piston chamber between the time when the valve shifts and port 15a is covered by piston 4 and 35 after piston 4 passes beyond port 15a and before the valve shifts to the forward position is so small as to be practically negligible. In a standard 40 riveting hammer having a nine inch stroke, the 45

shift passage 15 is a 5/32" drill hole while the restricted port 15 is a 1/16" drill hole. This makes the cross sectional area of the restricted port only 4/25 or less than 1/5 the area of the shift passage.

While the invention has been herein disclosed in what is now considered to be a preferred form, it is to be understood that the invention is not restricted to the specific details thereof but covers all changes, modifications, and adaptations within the scope of the appended claims.

I claim as my invention:

1. A fluid pressure tool comprising a cylinder, a piston reciprocable therein, a valve for controlling the distribution of the motive fluid and moving in timed relation with said piston, said valve having a flange, means for admitting motive fluid to one face of said flange to move the valve in one direction comprising a passage controlled by said piston, said passage terminating in a greatly restricted port immediately adjacent said valve flange, means controlled by said flange to admit live motive fluid to complete the shifting movement of said valve, and passages uncovered by said valve flange for utilizing the motive fluid admitted by said last-named means for effecting the rearward stroke of said piston.

2. A fluid pressure tool comprising a cylinder, a piston reciprocable therein, a valve for controlling the distribution of motive fluid and moving in timed relation with said piston, said valve having a shift area, means for admitting pressure fluid to said area to move the valve in one direction comprising a passage controlled by said piston, said passage opening against said area by a port whose cross sectional area is one-fifth or less the area of said passage, means uncovered by said valve to admit live motive fluid to said area to complete the shifting movement of said valve, and means controlled by said valve and utilizing live motive fluid admitted by said last named means to said valve area for effecting the rearward stroke of said piston.
